[57] CLAIM

The ornamental design for a dough guide suitable for
making taco salad shells, as shown and described.

DESCRIPTION

FIG. 1 is a perspective view of a dough guide suitable
for making taco salad shells showing my new design;
FIG. 2 is a top plan view thereof;
FIG. 3 is a side elevation view thereof;
FIG. 4 is a rear elevation view thereof;
FIG. 5 is a bottom plan view thereof; and,
FIG. 6 is a sectional view thereof along lines 6—6 of
FIG. 2.
